UNITED STATES PATENT OFFICE.

WALTER R. PADLEY, OF COOLIDGE, KANSAS.

TOURIST'S TENT.

1,009,783.

Specification of Letters Patent. Patented Nov. 28, 1911.

Application filed January 17, 1910. Serial No. 538,536.

To all whom it may concern:

Be it known that I, WALTER R. PADLEY, residing at Coolidge, in the county of Hamilton and State of Kansas, have invented certain new and useful Improvements in Tourists' Tents, of which the following is a specification.

This invention relates to certain new and useful improvements in portable shelters 10 of the tent type, and it primarily has for its object to provide a tent that is particularly designed for use as an automobile shelter, although its use is not limited thereto.

Generically the invention resides in the provision of a tent wherein the framing is so constructed that the greater part thereof can be made of pressed thin metal, and wherein means are provided for quickly 26 bringing the cover over the frame when set up or uncovering the frame, as the case may be.

In its more detailed nature the invention also resides in the provision of two collapsible end frames formed of parts hinged together and having braces to hold the parts in their proper relative positions, the end frames being joined by longitudinal struts or braces that connect with the end frames 30 at the joint thereof and assist the braces in sustaining the parts of the end frames in their proper positions.

The invention also provides a roll upon which the covering is wound and which will 35 act as a brace for joining the end frames, reels being provided upon the end frames upon which cables are wound, the cables passing over guards on the end frames and connecting with the covering on the roll 40 whereby the covering may be drawn upon the frame, the reels being connected together by a removable rod which also serves as a brace between the end frames.

In addition to the foregoing, the invention 45 also resides in those novel details of construction, combination and arrangement of parts, hereinafter described and illustrated in the accompanying drawings, in which:

Figure 1, is a perspective view illustrating the application of the invention as an automobile shelter. Fig. 2, is a detail perspective view of one end of the tent the covering being rolled up. Fig. 3, is an enlarged 55 detail perspective view of one of the joints in the end frame and the parts that coöper-

ate therewith. Fig. 4, is a detail perspective view of the presser roller and its parts detached. Fig. 5, is an enlarged central vertical longitudinal section of a portion of the end frame, showing the position of the parts when folded. Fig. 6, is a similar view showing the position of the parts when set up. Fig. 7, is an enlarged detail view of certain coöperative parts of the end frame 60 separated from one another. Fig. 8, is an enlarged detail perspective view of one end of one of the longitudinal braces or struts. Fig. 9, is a similar view looking from another direction. Figs. 10 and 11, are detail 70 perspective views of one of the winding-up drums and its coöperating parts. Figs. 12 and 13, are central vertical longitudinal sections of the winding-up drum and clutch showing the parts in their clutched and released positions, respectively. Figs. 14 and 15, are detail perspective views of the bearing for the cover roller. Fig. 16, is a detail central vertical longitudinal section of the central joint of one of the end frames. Fig. 80 17, is a detail perspective view of a part of the covering showing the brace rod therefor. Fig. 18, is a detail view showing a part of a tool for gripping the strut forks to release the same from the end frames. Fig. 19, is 85 a detail view of the tent collapsed, and the carrying case therefor.

Referring now to the accompanying drawings in which like numerals and letters of reference indicate like parts in all of the 90 figures, it will be seen that the improved tent comprises a pair of end frames 1 joined together by longitudinal braces or struts 20, hereinafter again referred to. The frames 1 are composed of the end braces 2 and the 95 intermediate members 3, which members are hinged together through their ears 5, by hinge pins or bolts 4 on which rollers 33 are journaled. Pivoted at 16 to the intermediate sections 3 of the end frame is a brace 14 100 having a shoulder 15 at its free end and laterally projected parts 15^a to ride in a slot-way 12 of a guide 11 that is secured at 13 within the channel member 2 of the end frame, the channel member 2 having slots 6 105 to permit passage of the catches 7 of a latch 8 that is secured at 9 to the member 2 and has a finger engaging portion 10, by means of which the latch may be lifted out of engagement with the brace 14. The end frame 110 members 2 and 3 adjacent to their joints 4 have apertures 17 to receive the fingers 18^a.

of the heads 18 of the struts 20 that connect the end frames together at their joints. The fingers 18^a are separated a distance sufficient to receive the rollers 33, as clearly shown in Figs. 2 and 3 of the drawings. Each finger 18^a has a notch 19 and a beveled end adjacent thereto whereby the fingers 18^a may be inserted into the apertures 17 and goes through notches 19 to interlock with the end frame members.

10 and 15 Each longitudinal strut 20 may be composed of an L-iron and joined at 22 with the heads 18, an adjustable joint being provided by forming the members 20 with slots 21 through which the connecting screws or bolts 22 may pass as clearly shown in Figs. 8 and 9 of the drawings.

The sections 3 of the end frames are joined together by a brace 30 which is of similar form to the brace 14 and has a shouldered end 32 and is pivoted at 31, as clearly shown in Fig. 16 of the drawings, the shouldered end 32 operating in the slotway 24 of a guide 23 secured to one of the end members 3 and 25, a latch 26 having latch stops 27 is secured to one of the sections 3 and co-operates with the shouldered end 32 of the members 30, the latches 26 as well as those designated 8 are resilient ones, and the latch 26 is secured at 28 and has a finger engaging portion 29, as shown in Fig. 16 of the drawings.

Each roller 33 has a groove 34 in which the cable 51 hereinafter again referred to is held by resiliently mounted guide rollers 35 having corresponding grooves 36 and mounted on shaft portions 37 of a rod which at 42 passes through apertures in the channel members 3 and is held in place by riveting at 43 or otherwise, as may be found desirable. The roller 35 is held on the bearing part 37 of the support by a washer 40 and cotter pin 41 on one side and a plate 38 having a collar 39 to embrace the support on the other side. A spring 44 holds the rollers 35 in contact with the roller 36. Bearings 45 are provided near the lower ends of one of the side members 2 of each end frame 1 to receive the bearing end 46 of the cover carrying roller on which the cover 50 for the tent is wound, a holding or latch member 47 being provided to retain the bearing end 46 in the respective bearing 45. A ratchet 48 is mounted on the roller end 46 and co-operates with a pawl 49 secured to the end frame member 2, the roller end 46 having a hollow portion to receive a crank 73, by means of which the roller may be turned when desired. Cables 51 connected to the cover 50 pass between the respective rollers 33 and 35, as clearly shown in Figs. 1 and 2 of the drawings, and wind on a drum 52 that is provided with a drum shaft 53 on which the drum 52 is mounted, the shaft 53 having bearing in the bearing parts 54 of a clip 58 which is secured to the end

frame member 2, the clip 58 having one of its bearings provided with clutch slots 59 to coöperate with a shifting clutch member 57 that reciprocates in a slot 61 in the shaft 53 and is spring pressed to lock with the 70 clutch part 59 of the bearing 58 by a spring 60. A short tubular member or rod 64 within the shaft 53 engages the shifting clutch member 57 to force it to release its engagement with the clutch notches 59, when the 75 shaft 53 is forced in the position shown in Fig. 13 of the drawings, the shaft 63 having a pin 66 to fit into a slot 65 in the shaft 53 and be engaged by a spring 56 mounted on the drum 52, the drum 52 having end 80 disks 54, one of which is provided with ratchet teeth 55 to coöperate with a pawl 67 that is pivoted at 68 to the end frame member 2 to prevent turning of the drum 52 in but one direction.

There are two drums 52 provided, one on each end frame and these drums are connected together by the rod 63 hereinbefore referred to, as shown in Figs. 10, 11, 12 and 13 of the drawings, whereby both drums 52 90 may be made to move in unison. The drum shaft 53 is hollow, as before stated and the outer end thereof is provided with a cross pin 62 so as to receive the forked end of the crank 73 whereby the shaft 63 with the drums 52 may be turned together to draw the covering over the frame from the position shown in Fig. 2 to the position shown in Fig. 1. 95

The cover 50 is wound on the cover carrying roller, as before stated, and its free longitudinal edge is provided with a stiffening rod 72 to which the cables 51 may be connected. The end flaps 69—70, in practice, are folded over, as shown in Fig. 1 when the cover is to be rolled up, and when it is desired that the end flaps be brought into use to close the ends of the shelter they may be pulled over the same somewhat in the manner indicated in Fig. 1 of the drawings. 100 105 110

When found desirable guy ropes 71 may be attached to the tent and stationed at 74 to sustain the structure, although, in practice, such ropes are necessary only in high winds. 115

In practice the entire tent may be "knock-down" and packed in a case 75, shown particularly in Fig. 19 of the drawings. In order to set up the tent the end frames are removable from the case and the sections are moved on their hinges until they assume the position indicated in Figs. 1, 2, 3 and 6 of the drawings, at which time the braces 14 and 30 will automatically come into position to be engaged by the latch portions 7 and 27 of the latches 8 and 26 respectively to hold the end frame sections in their relative positions. The longitudinal braces or struts 20 have their fingers 18* pushed 120 125 130

through the apertures 17 until they spring into place with the notches 19 in engagement with the ends of the apertures 17. The roll 46 is then placed in its bearings 45, as shown in Figs. 2, 14 and 15 of the drawings, and the rod 63 is inserted into the opposite ends of the shaft 53 of the reels 52 when such shafts are automatically released the clutches 57 and the latches 56 will automatically latch the shaft 63 to the respective reels. The operator then inserts the crank 73 into the end of the reel shaft 53 (the pawl 49 being released) and upon turning the crank 73 will wind the cable 51 onto the reels 52 and draw the cover 50 over away from the position shown in Fig. 2 of the drawings to the position shown in Fig. 1. After which, the pawl 49 may be brought into engagement with the ratchet 48 and the desired tension applied to the cover 50, it being understood that the pawl 67 will hold the reels from backward movement and keep the cover stretched taut over the frame.

In taking the tent apart the pawls 67 are released from their respective ratchets 55, the crank 73 is inserted in the end 46 of the cover carrying roller and the covering is rewound onto the cover carrying roller after which the rod 63 is removed and the roll 46 is removed from its bearings 45. The longitudinal struts or braces 20 are removed by gripping the fingers 18^a and squeezing them together by any suitable means, say, by the tool 76, shown in Fig. 19, until the notches 19 are brought out of engagement with the frame sections and the braces 20 removed. After this the latches 8 and 26 are moved to release the braces 14 and 30 respectively and the end frames may then be folded together, as shown in Figs. 5 and 19 of the drawings.

The entire tent can be packed into any suitable case 75, if desired.

While I have described my invention as adapted for an automobile shelter, I desire it understood that it may be made in any required size for any use desired.

In practice the framing parts may nearly all be made of pressed steel or other suitable light material. I do not wish to limit myself in any way in this respect. It will also be observed that the longitudinal braces or struts 20 not only serve to connect the end frames to one another, but by reason of the construction of the heads 18 and the manner of connecting the same with the end frame at the joint thereof afford an ample sustaining means for the end frame sections at such joint to give a maximum strength with minimum weight of parts. Furthermore in addition to the struts or braces 20, the rod 63 on the one side and the cover carrying rollers on the other side serve to brace the end frames together at their lower ends.

From the foregoing description taken in connection with the accompanying drawings, the complete construction, operation and advantages of my invention will be readily understood by those skilled in the art to which the invention appertains.

What I claim is:

1. A tent comprising a frame composed of a pair of end frames and longitudinal struts connecting said end frames together, bearings carried by said end frames, and a roll mounted in said bearings, a covering wound on said roll, drums carried by said end frames, guides carried by said end frames, a cable passing over said guides and wound on said drums and connected with said covering, and means in virtue of which said drums may be turned to bring said covering over said frame.

2. In a tent, a pair of end frames, struts connecting the upper extremities of said end frames together, said end frames having bearing members at their lower extremities, a cover carrying roller having portions mounted in one of said bearings of each end frame to form a brace connection between said end frames, a brace connection between said end frames opposite to said roller, and means co-operative with said brace connection for drawing said cover over said frame.

3. In a tent, a pair of end frames formed of sections hinged together said sections having apertures, braces connecting said sections at their joints, longitudinal struts connecting said end frames together and including heads having fingers projecting through said apertures in said end frame sections adjacent to the joints thereof and interlocking therewith, a covering for said tent and mechanical means for extending said covering over said frame and removing said covering from over said frame.

4. In a tent, a pair of end frames formed of sections hinged together said sections having apertures, braces connecting said sections at their joints, longitudinal struts connecting said end frames together and including heads having fingers projecting through said apertures in said end frame sections adjacent to the joints thereof and interlocking therewith, a covering for said tent, mechanical means for extending said covering over said frame and removing said covering from over said frame, said last named means comprising a roll on which said covering is wound, winding drums, and a cable connecting said covering with said winding drums and passing over said struts.

5. In a tent, a pair of end frames formed of sections hinged together said sections having apertures, braces connecting said sections at their joints, longitudinal struts connecting said end frames together and in-

cluding heads having fingers projecting through said apertures in said end frame sections adjacent to the joints thereof and interlocking therewith, a covering for said tent, mechanical means for extending said covering over said frame and removing said covering from over said frame, said last named means comprising a roll on which said covering is wound, a cable connecting 10 said covering with said winding drums and passing over said struts, and means for maintaining said covering taut.

6. In a tent, a pair of end frames formed of sections hinged together said sections having apertures, braces connecting said sections at their joints, longitudinal struts connecting said end frames together and including heads having fingers projecting through said apertures in said end frame 15 sections adjacent to the joints thereof and interlocking therewith, a covering for said tent, mechanical means for extending said covering over said frame and removing said covering from over said frame, said last 20 named means comprising a roll on which said covering is wound, a cable connecting said covering with said winding drums and passing over said struts, means for maintaining said covering taut, guide rollers carried by said end frames over which said cables pass, and presser rollers for maintaining said cable on said guide rollers.

7. In a tent, a pair of end frames formed of sections hinged together said sections having apertures, braces connecting said sections at their joints, longitudinal struts connecting said end frames together and including heads having fingers projecting through said apertures in said end frame 25 sections adjacent to the joints thereof and interlocking therewith, a covering for said tent, mechanical means for extending said covering over said frame and removing said covering from over said frame, said last 30 named means comprising a roll on which said covering is wound, winding drums, a cable connecting said covering with said winding drums and passing over said struts, means for maintaining said covering taut, 35 said last named means comprising ratchet and pawl devices carried by said drums and said roll.

8. In a tent, a pair of end frames formed of sections hinged together said sections having apertures, braces connecting said sections at their joints, longitudinal struts connecting said end frames together and including heads having fingers projecting through said apertures in said end frame 40 sections adjacent to the joints thereof and interlocking therewith, a covering for said tent, mechanical means for extending said covering over said frame and removing said covering from over said frame, said last 45 named means comprising a roll on which said covering is wound, a cable connecting said covering with said winding drums and passing over said struts, means for maintaining said covering taut, and guide rollers

carried by said end frames over which said cables pass.

8. In a tent, a pair of end frames formed of sections hinged together said sections having apertures, braces connecting said sections at their joints, longitudinal struts 55 connecting said end frames together and including heads having fingers projecting through said apertures in said end frame sections adjacent to the joints thereof and interlocking therewith, a covering for said tent, mechanical means for extending said covering over said frame and removing said covering from over said frame, said last named means comprising a roll on which said covering is wound, a cable connecting 60 said covering with said winding drums and passing over said struts, means for maintaining said covering taut, guide rollers carried by said end frames over which said cables pass, and presser rollers for maintaining said cable on said guide rollers.

9. In a tent, a supporting frame, a covering therefor, a roll on which said covering is wound, bearings carried by said frame in which said roll is supported, a pair of 75 winding-up drums carried by said frame, cables connecting said drums with said covering and passing over said frame, clutch devices for locking said drums inoperative, a removable connecting rod between said 80 drums, and automatically actuated devices coöperating with said connecting rod for releasing said drum clutch devices when said connecting rod is in position.

10. In a tent, a supporting frame, a covering, cables passing over said frame and connected with said covering in virtue of which said covering may be drawn over said frame, said frame including pivoted frame sections, guide rollers mounted on the pivots 85 of said frame sections over which said cables pass, and means for maintaining said cables 90 on said guide rollers.
